6 Claims. (Cl. 29—203)

1

This invention relates to assembling fixtures and more particularly to fixtures for assembling potentiometer cards and associated elements in potentiometer housings.

This invention is related in general to assembling potentiometer cards, insulating strips and slip rings in multiple groove type cylindrical potentiometer housings. The potentiometer housings may have one or more annular grooves provided therein for receiving a fixed number of elements required to make up a single potentiometer unit. In one particular type of potentiometer each annular groove of the potentiometer housing has assembled therein a group of elements comprising an outer insulating ring, a potentiometer card, two intermediate insulating rings, a slip ring and an insulated bridge member. The potentiometer card has its beginning turn and its end turn marked and is positioned in the housing so that one of the marked turns is directly opposite scribe marks provided on the face of the respective partition which forms the particular annular groove involved.

The potentiometer card and the slip ring must have their contacting surfaces in the same plane, which plane must be slightly above the face of the housing, while the various insulating rings must be positioned substantially below this contacting plane. The bridge must be positioned in line with the outer insulating ring, and have its top face extending above the contacting plane of the potentiometer card, so that it will lift the potentiometer brush off the card when it is moving from the end of the card to the beginning thereof or vice versa.

One proposed method of assembling the various elements into the annular groove was by hand, in which case each element was partially positioned in the groove in its proper position, and then the entire group was forced into the groove. In forcing the group of elements into the groove, relative movement between the individual elements resulted, and when it was necessary to adjust only one of the elements, such adjustment usually disturbed the other elements.

When any movement occurred between the potentiometer card and the various insulating rings, it usually produced a series of loose turns on the potentiometer card which seriously affected the electrical characteristics of the card or broke or

5 loosened the leads secured to the beginning and end turns of the card. In addition, it was very difficult to position each individual element at its proper elevation with respect to each other and to the face of the potentiometer housing.

Thus, hand assembly of the individual elements within the annular groove proved to be a very tedious and time-consuming operation. Furthermore, many units were unsatisfactory because of above-described defects produced by such assembly.

An object of the invention is to provide new and improved assembling fixtures.

Another object of the invention is to provide an assembly fixture for assembling various elements required to make up a cylindrical potentiometer.

In accordance with a specific embodiment of the invention there is provided means for effecting a loose pre-assembly of the various elements to be assembled in the groove of a potentiometer housing, means for clamping the elements tightly together as a composite unit in the fixture and means for transferring the unit from the fixture to the potentiometer housing, during which transfer no relative movement occurs between the individual elements of the unit.

A clear understanding of the invention may be had from the following detailed description of a specific embodiment thereof, when read in conjunction with the appended drawings, in which:

Fig. 1 is a plan view of an assembling fixture forming a specific embodiment of the invention;

Fig. 2 is a vertical, sectional view taken along line 2—2 of Fig. 1;

Fig. 3 is an enlarged, fragmentary, vertical view of a portion of the fixture shown in Fig. 1, and having portions thereof broken away to illustrate some of the internal structure;

Fig. 4 is a fragmentary, vertical, right-hand view of a portion of the apparatus shown in Fig. 2;

Fig. 5 is a fragmentary, front vertical view of a portion of the apparatus shown in Fig. 1;

Fig. 6 is a horizontal, sectional view taken along line 6—6 of Fig. 2;

Fig. 7 is an enlarged, fragmentary, vertical, sectional view of a portion of the apparatus;

Fig. 8 is an exploded view showing the various

3

elements to be assembled together in a potentiometer housing;

Fig. 9 is a fragmentary, vertical sectional view showing the various elements of Fig. 8 positioned in the apparatus shown in Figs. 1 and 2;

Fig. 10 is a fragmentary, vertical sectional view taken along line 10—10 of Fig. 5;

Fig. 11 shows the assembling fixture inverted and positioned on a potentiometer housing, and

Fig. 12 shows the position of the elements in the potentiometer housing after they have been transferred from the fixture.

Referring now to the drawings, particularly Fig. 2, there is shown a cylindrical support 20 having a bore 21 and a counterbore 22 adjacent to the upper face of the support for receiving and supporting an assembling fixture 23. The support 20 serves to hold the assembling fixture 23 in a substantially stationary position while a potentiometer card and its associated strip-like elements, hereinafter to be described, are assembled in the fixture 23. The fixture 23 comprises a ring 24 having a bore 25 adjacent to its upper face, a counterbore 26 adjacent to its lower face and an annular shoulder 27 formed at the point where the counterbore 26 and the bore 25 communicate with each other. A base 30 has a cylindrical body portion 31 positioned within the ring 24 adjacent to the counterbore 26 and is provided with an integral flange 32, the periphery of which is substantially flush with the periphery of the ring 24. The flange 32 is positioned against the bottom face of the annular ring 24 and secured thereto by a plurality of screws 33—33, and is provided with four arcuate slots 35—35 spaced equidistantly around the periphery 34 of the body portion 31 (Fig. 6). The inner wall of the slots 35—35 is vertically aligned with the periphery 34 and the outer wall of the slots is vertically aligned with the bore 25 of the ring 24.

An ejector ring 36 is slidably positioned around the body portion 31 and is provided with four arcuate-shaped legs 37—37 slidably positioned in the arcuate slots 35—35 provided in the flange 32. The flange 32 is wider than the bottom face of the flange 32 and it extends beyond the counterbore 26 and thereby provides an annular shoulder 38 similar to the shoulder 27 provided in the ring 24. The ring 36 is provided with an annular flange 40, the periphery of which slidably engages the counterbore 26 of the ring 24. Since the flange is free to slide in the counterbore 26 between the shoulder 27 and the shoulder 38, the travel of the ring 36 is fixed by these shoulders. The upper face of the ring 36 is provided with an outer groove 41 and an inner groove 42 which form an outer annular ring 43 between the periphery of the ring 36 and the groove 41 and an inner annular ring 44 between the grooves 41 and 42 (Fig. 7). The bottoms of the grooves 41 and 42 are in the same plane which plane is indicated by the surface marked 45 (Fig. 7). The annular rings 43 and 44 are cut away at points 46, 47, 48 and 50, as shown in Fig. 1, in which case only the surface 45 is present at these points.

At the point 50 a recess 51 (Fig. 3) is cut in the ring 36 and has its bottom 52 substantially below the bottom 45 of the annular grooves 41 and 42. The groove 51 is provided on the assembly ring 36 directly opposite the word "bridge" which is scribed on the upper face of the ring 24 adjacent to its inner periphery. A sight hole 53 (Fig. 4) is provided directly opposite the points 46 and 47 where the annular rings 43 and 44 have been cut away to the surface 45. Each sight hole 53 com-

4

municates with the bottom of a horizontal arcuate slot 54 cut in the periphery of the ring 24 so that a substantially thin wall section exists at the sight hole 53, whereby the surface 45 at the points 46 and 47 may be easily viewed therethrough. An elongated sight hole 55 (Fig. 5) is provided at the bottom of a tapered aperture 56 also provided in the periphery of the annular ring 24 (Fig. 2). A thin wall section 57 remains above the elongated sight hole 55 and has an index marked 58 centrally scribed thereon. An index mark 60 (Fig. 12) is scribed across the bottom wall of the sight hole 55 provided in the tapered aperture 56 directly in line with the index mark 58.

A resilient clamping ring 62 (Fig. 2) is positioned on the upper face of the base 30 and is provided with a plurality of substantially circular apertures 63—63 adjacent to its outer periphery 64. The apertures 63—63 break through the inner periphery 65 of the base of the ring 62 and together with a saw cut 66 provided across the ring 62 serve to make the ring 62 resilient about its outer periphery 64. The ring 62 has a tapered bore 67 which tapers outwardly from the inner base periphery 64 to a point on the top face thereof adjacent to the outer periphery 64 of the ring. A cam 68 is provided with a tapered periphery which slidably engages the tapered surface 66 provided in the clamping ring 62 and is provided with a bore 70 and a large counterbore 71. A clamping bolt 72 is rotatably positioned in the bore 70 of the cam 68 and has provided on the upper end thereof a large circular head 73 which is positioned in the counterbore 71. The head 73 is provided with a hexagonal aperture 74 for receiving a suitable socket wrench (not shown) which may be used to impart a rotary movement to the bolt 72. The lower end of the bolt 72 is threadedly mounted in a tapped bore 75 provided in the body portion 31 of the base member 30. A compression spring 76 is positioned over the bolt 72 between a shoulder 78 formed by a counterbore 77 provided in the body portion 31 and the tapped bore 75 and the under surface of the cam 68 and serves to urge the cam plate upwardly as the bolt 72 is backed out of the tapped bore 75. An annular assembling groove 79 is formed between the bore 25 of the ring 24 and the outer periphery 64 of the resilient ring 62, in which the various potentiometer groove elements shown in Fig. 8 are to be assembled as hereinafter to be described. The groove 79 is variable in width due to the fact that the periphery 64 of the ring 62 may be expanded by drawing the cam plate 68 downwardly by turning the bolt 72 in a clockwise direction. As the cam plate is drawn downwardly against the action of the spring 76, its tapered periphery serves to expand the ring 62 and decrease the width of the groove 79. When the cam plate 68 is positioned substantially as shown in Fig. 2, the resilient ring is in its retracted position, that is, its periphery 64 is not flush with the periphery 34 of the body portion 31, whereby the groove 79 is at its maximum width, and the fixture 23 is in its normal element receiving position.

A pin 80 is rigidly secured in a vertical bore 81 provided in the body portion 31 of the base member 30 and slidably engages a vertically aligned bore 82 provided in the cam 68. The pin 80 serves to prevent any rotary movement of the cam 68 when the bolt 72 is being rotated. A pin 83 is rigidly secured in a bore 84 provided in the base 20 and slidably engages the vertically aligned bore

81 provided in the body portion 31 of the base member 30. The pin 83 serves to maintain the fixture 23 in a stationary position during the assembly operation to be hereinafter described.

Fig. 11 shows a portion of a potentiometer housing 90 which is provided with a plurality of annular grooves 91-91, in which are to be assembled a potentiometer card and associated elements shown in Fig. 8. Since the same problems arise in assembling elements similar to those shown in Fig. 8 in each of the annular grooves 91-91 of the potentiometer housing 90, the assembly of the elements in the outer groove 91 only will be discussed. The various elements which are to be assembled in the outer groove 91 of the housing 90, as shown in Fig. 8, comprise a metallic slip ring 95 having an offset end 96 which overlaps the opposite end of the ring and a very smooth, contacting surface 97, a suitable lead 98 secured to the slip ring adjacent to the offset end 96, an insulating ring 100 of sufficient length to completely surround the slip ring 95 with the exception of the offset end 96, a second insulating ring 101 of sufficient length to completely surround the insulating ring 100 and having its open end diametrically opposite the open end of the ring 100, a potentiometer card 102 having a contacting surface 103, its beginning turn marked as indicated at 104 and leads 105-105 secured to the beginning and end turns of the card, an outer insulating ring 106 of sufficient length to completely surround the potentiometer card 102 except for that portion of the card between the leads 105-105, a bridge member 107 having a contacting surface 108 and an insulating envelope 110 in which the bridge member 107 is placed before being positioned against the potentiometer card 102 and between the ends of the insulating ring 106.

The width of the annular groove 91 is substantially equal to the accumulated thickness of the various elements shown in Fig. 8 which are to be assembled in the groove whereby a very tight fit of the elements in the groove is assured. Because of the tight fit required between the elements and the groove 91, hand assembly of each individual element in the groove is a very difficult and time-consuming operation. Since the potentiometer card 102 comprises a plurality of turns of very fine wire and has secured thereto very delicate leads 105-105, any relative movement between the insulating rings 101 or 106 and the card 102 may result in a serious damage to the windings or leads of the potentiometer card. In order to overcome these difficulties, it is necessary to provide a relatively loose preassembly of the elements in a fixture such as that hereinabove described and transfer the various elements as a composite unit to the groove 91 of the potentiometer housing 90.

The various elements to be assembled in the groove 91 are first positioned in the assembling groove 79 of the fixture 23 in the following manner:

The bolt 72 is rotated so as to allow the spring 76 to urge the cam 67 upwardly which in turn allows the resilient clamping ring 62 to retract to its smallest diameter. When the clamping ring 62 is in this retracted position, the annular groove 79 (Fig. 2) between the bore 25 of the ring 24 and the outer periphery 64 of the clamping ring 62 is slightly wider than groove 91 of the potentiometer housing 90. The slip ring 95 is placed in the groove 79 with its contact face 97 abutting the bottom 45 of the inner groove

42 (Fig. 9), and with the offset end 96 positioned in the cutout portion 50 provided on the face of the assembly ring 36 adjacent to the groove 51. The intermediate insulating ring 100 is then positioned in the groove 79 so that it completely surrounds the slip ring 95 with exception of the offset end 96 and has its bottom face resting completely on the face of the ring 44. The second intermediate insulating ring 101 is positioned in the groove 79 so that it completely surrounds the insulating ring 100 and covers the offset end 96 of the slip ring 95, in which case its ends are diametrically opposite the ends of the insulating ring 100.

15 The potentiometer card 102 is then positioned in the groove 79 with the beginning turn 104 directly in line with the scribe mark 60 (Fig. 10) provided on the bottom wall of the sight hole 55 and having its contacting face 103 positioned against the bottom 45 of the annular groove 41 (Fig. 9). The insulating ring 106 is then positioned in the groove 79 so that it completely surrounds the potentiometer card 102 with the exception of the ends of the card on which the leads 105-105 are secured. The bridge 107 is placed in the insulating envelope 110 with its contacting surface 108 extending beyond the sides of the envelope, and this unit is positioned in the groove 79 against the card and between the ends of the ring 106 so that its exposed end 108 engages the recess 51 provided in the assembly ring opposite the word "bridge" scribed on the face of the ring 24.

20 It will be noted that the slip ring 95 and the 35 potentiometer card 102 are positioned on the bottom 45 of the annular grooves 41 and 42 and thereby have their contact surfaces 97 and 103, respectively, in the same plane, whereas the insulating rings 100, 101 and 106 are positioned on the face of the annular rings 43 and 44 which is substantially above the bottom 45. The bridge 107, however, is positioned in the recess 51 so that its face 108 abuts the bottom 52 thereof which places the face of the bridge substantially below the bottom 45 or below the contacting surface of the slip ring and potentiometer card assembled in the groove 79.

40 As each individual element is positioned in the groove 79, in the order described hereinabove, its position with respect to the bottom 45 of the grooves 41 and 42 or the face of the annular rings 43 and 44 is determined by the sight holes 53-53 and 55. For example, when the slip ring 95 is positioned in the groove 79, its contacting surface 97 must abut the bottom 45 of the groove 42. The sight holes will readily indicate whether or not the slip ring is properly seated in the groove 42 around its entire periphery. Likewise, the sight holes will indicate whether or not the various elements subsequently assembled in the fixture groove are properly positioned on the face of the ejector ring 36.

45 When the various elements have been assembled in the groove 79 as described above, a suitable tool is inserted in the hexagonal aperture 73 and actuated to turn the bolt 72 in a clockwise direction and draw the cam 68 downwardly against the action of the spring 76. As the cam 68 is drawn downwardly, its tapered periphery engages the tapered bore 67 of the clamping ring 62 and spreads the periphery of the clamping ring outwardly against the slip ring 95 positioned in the groove 79 and thereby squeezes the various elements positioned therein tightly together to 50 form a composite unit. When the various ele-

ments have been clamped tightly together in the groove 79, the fixture 23 is removed from the support 30, inverted and positioned on the face of a potentiometer housing such as the housing 90 (Fig. 11) so that the bottom of the potentiometer card 102 extends into the outer groove 91. The fixture 23 is positioned on the housing so that the scribe mark 58 provided above the sight hole 55 is aligned with a scribe mark 113 provided on the potentiometer housing 90. In this way the beginning turn 104 of the potentiometer card 102 is properly positioned with respect to the potentiometer housing 90.

When the fixture 23 and the potentiometer housing 90 bear this relation to one another, the two pieces are placed as a unit on a base plate 114 of an arbor press (not shown) of standard design and having a reciprocable ram 115. The arbor press is actuated so that the ram 115 is urged downwardly and engages the legs 31-37 provided on the ejector ring 36. As the ram 115 moves downwardly, it causes the ejector ring 36 to slide within the fixture 23 and eject the composite unit clamped in the groove 79 from the fixture 23 into the groove 91 of the housing 90, during which ejection no relative movement occurs between any of the individual elements of the composite unit being transferred. When the ram 115 has descended to the extent that the flange 40 of the ejector ring 36 has travelled from the shoulder 38 and abuts the shoulder 27, the composite unit has been completely inserted in the groove 91 (Fig. 12) and the face of the annular rings 43 and 44 is flush with the face of the housing 90. The potentiometer card 102 and the slip ring 95 have their contacting faces in the same plane and are substantially above the top face of the various insulating rings 100, 101 and 106. When the various elements have been completely transferred from the groove 79 of the fixture 23 to the groove 91, the arbor press is actuated to raise the ram 115 upwardly whereupon the fixture 23 is removed from the face of the potentiometer housing.

It will be noted that the composite unit travels only a relatively short distance from the groove 79 when it enters the groove 91 of the potentiometer housing 90. During the remaining travel of the composite unit it is dually supported by the fixture groove and the groove 91 of the housing 90, whereby the individual elements remain in a tightly clamped condition during the entire travel of the composite unit. It will also be noted that while the composite unit is being ejected from the groove 79 by the ejector ring 36, no relative movement can occur between the individual elements of the composite unit because each individual unit is backed up by the face of the ejector ring. In other words, the force applied to the ejector ring by the ram 115 is distributed equally to each element of the composite unit, whereby there is no tendency for any individual element thereof to move separately of the other elements.

The above-described fixture facilitates a rapid and accurate assembly of a potentiometer card and its associated elements in an annular groove of a potentiometer housing. The fixture provides for a relatively loose pre-assembly of a potentiometer card and associated elements in a groove provided therein so that the delicate windings of the card are not damaged during the pre-assembly operation. Since no relative movement occurs between the individual elements of the composite unit during the ejection operation, the

potentiometer card winding is further protected from damage.

The fixture 23 is designed to assemble a potentiometer card and its associated elements in the outer groove 91 of the potentiometer housing 90. In order to assemble a potentiometer card and its associated elements into the remaining annular grooves 91-91, an assembling fixture similar to fixture 23 must be used, but of such size that the diameter of the assembling groove formed therein is equal to the diameter of the particular groove of the housing in which the elements are to be assembled. The assembling procedure described hereinabove for fixture 23 is followed for each assembling fixture and its respective groove in the housing 90.

While the above-described invention is particularly well adapted to assemble a potentiometer card and its associated elements into annular grooves provided in potentiometer housings, it may be readily adapted to assemble a plurality of strip-like elements into a groove of any desired shape without departing from the spirit and scope of the invention.

What is claimed is:

1. A fixture for assembling potentiometer cards and associated strip-like elements in potentiometer housings, which comprises a cylindrical body member having a central bore therethrough, a base member having an annular flange secured to the bottom of said body member and a cylindrical body portion extending partially into said central bore, said flange being provided with a plurality of arcuate slots, an annular resilient clamping ring positioned on top of body portion of said base so as to form a groove with the central bore provided in the body member in which a potentiometer card and its associated strip-like elements may be assembled in a relatively loose edge-wise position with respect to each other, said resilient ring having a tapered bore therethrough, a ring slidably positioned in the lower portion of said central bore and having a plurality of integral legs which extend through said arcuate slots provided in the flange of the base member, the face of said ring being positioned to form the bottom of said groove and having a pair of annular grooves and a pair of annular rings against which the potentiometer card and its associated elements are seated when said card and elements are positioned in said groove, a plurality of sight holes provided about the periphery of the body member for viewing the position of the card and elements with respect to the grooves and rings provided on the face of the ring, a cam plate having a tapered periphery in engagement with the tapered bore of said resilient ring, and a stud threadedly mounted in the body portion of the base member and having a flanged head thereon in engagement with said cam plate, whereby when the stud is rotated it draws the tapered cam plate into the tapered bore of the resilient ring and expands said ring so as to decrease the width of the groove and clamp the potentiometer card and associated elements into a composite unit between the central bore and the clamping ring.
2. An apparatus for assembling potentiometer cards and associated elements in an annular groove provided in a potentiometer housing, which comprises a member having an annular groove in which a potentiometer card and its associated insulating elements may be positioned in a relatively loose edge-wise position, said groove having an adjustable inner wall so that

the width of the groove may be decreased after the potentiometer cards and insulating elements are positioned in the groove, slidable means normally positioned at the bottom of said annular groove against which the edges of the individual elements assembled in the groove are positioned, means provided on the member for expanding the inner wall of said groove so as to clamp the individual elements together in the groove to form a composite unit, and means provided on the slidable means for effecting movement of the slidable means so as to eject the composite unit from said groove, whereby when said member is placed adjacent to a potentiometer housing movement of the slidable means serves to slide the composite unit from the groove in the member into a groove provided in said potentiometer housing.

3. An apparatus for assembling potentiometer cards and associated strip-like elements in an annular groove provided in a potentiometer housing, which comprises a member having an annular groove in which a potentiometer card and its associated strip-like insulating elements may be assembled in a relatively loose edge-wise position with respect to each other, said groove having an expandable inner wall so that the width of the groove may be decreased after the potentiometer card and the insulating elements are positioned therein, a slidable member positioned in the annular groove so that a face thereof forms a movable bottom for said groove, the face of said slidable member forming the bottom of the groove having means provided thereon for aligning the edges of the potentiometer card and the insulating elements at different elevations with respect to each other, means provided on the member for expanding the inner wall of said groove so as to decrease the width of the groove and clamp the potentiometer card and its insulating elements together in the assembling groove as a composite unit, and means provided on the slidable member and projecting externally of the member whereby the slidable member may be moved so as to completely eject the clamped composite unit from the groove, whereby when said member is placed adjacent to a potentiometer housing movement of the slidable means serves to slide the composite unit from the groove in the member into a groove provided in said potentiometer housing.

4. An apparatus for assembling potentiometer cards and associated strip-like elements in an annular groove provided in a potentiometer housing, which comprises a base having an annular groove therein in which a potentiometer card and its associated strip-like elements may be assembled in a relatively loose edge-wise position with respect to each other, means provided on the base for orientating the potentiometer card in predetermined position with respect to the base, said groove having an expandable inner wall so that the width of the groove may be decreased after the potentiometer card and the associated elements are positioned therein, an annular member slidably positioned in the groove so one face thereof forms a movable bottom for said groove, the face of said slidable member forming the bottom of said groove having means provided thereon for positioning the edges of the potentiometer card and its associated elements at different elevations with respect to each other, means for expanding the inner wall of said groove to clamp the potentiometer card and its associated elements together in the assembling

groove as a composite unit, means provided on the slidable member and projecting externally of the base so that the slidable member may be moved to the top of the assembling groove and completely eject the composite unit therefrom, and means provided on the annular member for limiting the movement of the annular movement within said groove, whereby when the base is positioned over a potentiometer housing so that the orientating means is properly aligned therewith movement of the slidable member serves to slide the composite unit from the groove in the base into a groove provided in the potentiometer housing a predetermined distance.

5. An apparatus for assembling potentiometer cards and associated elements in an annular groove provided in a potentiometer housing, which comprises a base having an annular groove therein in which a potentiometer card and its associated elements may be assembled in a relatively loose edge-wise position with respect to each other, said groove having an expandable inner wall, an annular member slidably positioned in the groove so that one face thereof forms a movable bottom for said groove, the face of said slidable member forming the bottom of said groove having means provided thereon for positioning the edges of the potentiometer card and its associated elements at different elevations with respect to each other, means provided on the base for determining whether the potentiometer card and its associated elements are properly seated on the bottom of the groove, means for expanding the inner wall of said groove so as to decrease the width of the groove and clamp the potentiometer card and its associated elements together in the assembling groove as a composite unit, and means provided on the slidable member and projecting externally of said base so that the slidable member may be moved to the top of the groove and thereby completely eject the composite unit therefrom, whereby when said member is placed adjacent to a potentiometer housing movement of the slidable means serves to slide the composite unit from the groove in the member into a groove provided in said potentiometer housing.

6. An apparatus for assembling potentiometer cards and associated strip-like elements in an annular groove provided in a potentiometer housing, which comprises a base having an annular groove in which a potentiometer card and its associated strip-like elements may be assembled in a relatively loose edge-wise position with respect to each other, means provided on the base for orientating one end of the potentiometer card in a predetermined position in the groove, said groove in the base having an expandable inner wall, an annular member slidably positioned in the groove so that one face thereof forms a movable bottom for said groove, the face of said annular member forming the bottom of the groove having means provided thereon for positioning the edges of the potentiometer card and its associated elements at different elevations with respect to each other, means provided on the base for determining whether the individual elements are properly seated on the bottom of the groove, means for expanding the inner wall of said groove to decrease the width of the groove and clamp the potentiometer card and its associated elements together in the groove as a composite unit, and means associated with the slidable member and projecting externally of said base so that the slidable member may be

11

actuated to move the bottom of the groove to the top of the groove and thereby eject the composite unit therefrom, whereby when the base is positioned over a potentiometer housing so that the orientating means of the base is properly aligned with the housing movement of the slidable member serves to slide the clamped composite unit from the groove in the base into the groove provided in the potentiometer housing.
